UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

COATING BOOT AND SHOE PARTS

Original application filed November 22, 1920, Serial No. 425,743. Divided and this application filed January 28, 1928. Serial No. 250,130.

This invention relates to methods of coating boot and shoe parts and is herein exemplified with especial reference to applying cement to the foxing areas of shoes.

5 In the manufacture of shoes of the tennis type the lower portion of the lasted upper around the periphery of the shoe is coated with a band of cement for the purpose of securing a foxing strip which is made of gum 55 rubber and assists in the attachment of a rubber sole. It is important that the band of cement be applied accurately in order to produce a sharply defined line of demarcation between the coated and the uncoated areas. 60
10 If the band of cement extends above the upper edge of the foxing strip, it will deface the upper, especially if the shoes have uppers of white or light-colored material. On the other hand, if the cement does not extend fully to 65 the upper edge of the foxing strip, this strip will not be properly secured to the shoe and the consequent gaping will be detrimental to the appearance of the shoe and may lessen materially the life of the shoe due to accidental 70 separation between the foxing strip and the shoe upper. Heretofore the application of cement to the foxing areas of shoes has been usually effected manually, the operative working gradually about the foxing area with 75 a brush held in the hand. This procedure, however, is obviously slow and, depending for its success upon the skill of the operative, is at best uncertain.

One object of the invention is to provide an 80 improved method of applying cement to the foxing area of a shoe by means of which the line of demarcation between the uncemented part of the shoe upper and the foxing area to 85 which cement is to be applied for the attachment of a foxing strip may be accurately determined without reducing either the quantity or the quality of the work which can be turned out.

In carrying out the method of the present 90 invention, as herein exemplified, a flexible shielding member is interposed between the cement-applying means and the shoe to define the exposed foxing area around the lower part of the shoe to which cement is to be applied, and cement is applied to the exposed 95

area adjacent to the shielded area. As herein illustratively described, the operator positions the shoe in a predetermined relation to the cement-applying device, interposes a flexible imperforate shielding member between the cement-applying device and the area to be protected, and causes relative movement between the applying member and the shoe to transfer the point of application of cement around the foxing area. 100

An improved machine, by means of which my method may be successfully carried out, is illustrated and described herein, this machine embodying the invention claimed in my co-pending application Serial No. 425,743, originally filed Nov. 22, 1920, of which application this application is a division. 105

In the accompanying drawing,

Fig. 1 illustrates in perspective a machine by the aid of which my invention may be practised; and 110

Fig. 2 is a transverse section through the elements of that machine more closely associated with the work. 115

The illustrated foxing cementing machine by the aid of which the method of the present invention may advantageously be practised comprises a suitable frame 10 in which is rotatably mounted a shaft 12, having fixed at one extremity a fluid applying member, here shown as a brush 14. The shaft and brush are rotated from a convenient source of power by means not shown. The brush is supplied with coating fluid, as cement, from a receptacle 16, through a conduit 18 passing through the frame to a casing 20, which surrounds the upper portion of the brush. The flow of cement through the conduit may be controlled by a valve 22. Between the casing and brush, on the down-going side of the latter in its rotation, is a gate 24 to limit the passage of cement in this direction, its relation to the periphery of the brush being controlled by a screw 26 threaded into the top of the casing. Beneath the shaft 12 there is mounted upon a frame, by means of a screw-and-slot connection 28, permitting adjustment toward and from the brush, a work-rest 30 for 120

positioning a shoe in predetermined relation to the applying member. In the present instance, since this is to be used in contact with the bottom of a lasted shoe to present the foxing area to the brush, the extremity 32 of the rest is inclined to help the operator to position this surface of the upper properly with respect to the brush.

Adjacent to the applying surface of the brush is a segmental guide member 34, which may be formed of sheet metal. The guiding portion proper of this member, appearing at 36, is concentric to the periphery of the brush, and is U-shaped in cross-section, the legs of the U extending laterally of the brush, the lower being longer and projecting beneath the ends of the brush fibers. The upper leg of this portion 36 is cut away, so that its inner extremity lies outside the edge of the brush. The guide member 34 is shown as supported upon a bracket 38 extending from one side of the machine, it being secured thereto by a bolt 40 passing through a horizontal slot 42 in the bracket. This connection allows the guide member to be moved transversely of the brush, for a purpose which will hereinafter appear.

Carried at one side of the frame is a bracket 44, bearing at its upper extremity a support, as a reel 46, for a shielding strip 48, which strip may be of any suitable flexible material, paper being convenient. A friction device 49, associated with the reel, prevents the too free drawing-off of the strip. From the reel the strip passes downwardly and through the U-portion of the guide member, its inner edge extending beyond the lower wall of the U, and being held somewhat separated from the brush and concentric therewith. The direction in which the strip approaches the guide member is preferably tangential, and upon the opposite side, the strip leaves the guide member also in a generally tangential direction, passing upwardly between a pair of feed-rolls 50 and 52 rotatable upon the frame. The roll 50, as illustrated, is an idle bed-roll, it being flanged to prevent lateral movement of the strip out of engagement with its surface. The roll 52 may have extending about it circumferential corrugations 53, which reduce the area contacting with the strip-surface carrying a certain amount of cement. The roll 52 is secured upon one end of a shaft 54 journaled in the frame of the machine, and having at its opposite extremity a ratchet-wheel 56. With the teeth of this wheel cooperates a pawl 58, pivoted upon a lever 60 arranged to swing upon the end of the shaft 54. Articulated to the lower end of the lever is an eccentric rod 62, the strap of which surrounds an eccentric 64 fast upon the shaft 12. It will be seen that for each complete rotation of the brush shaft 12, the eccentric may be caused to move the pawl 58 through the

length of one or more of the ratchet teeth, as may be desired, thus through the contact of the roll 52 of the strip, advancing the latter to draw off from the reel 46 and present to the applying brush fresh portions of the strip.

In using the machine for cementing tennis shoe uppers, such as shown at S in Fig. 2 of the drawings, the lasted shoe is presented to the brush by the operator, being guided over and positioned in predetermined relation to the applying brush by the inclined end 32 of the work-rest. In preparation for this, the guide member 34 has been adjusted by means of its bolt 40 transversely of the brush to interpose a shield between the brush and the shoe, the shielding member or strip 48 entirely covering such a portion of the applying surface of the brush that the distance between the inner edge of said strip and the opposite side of the brush substantially equals the width of the surface to be coated. The operator, holding the work in the hands, turns it to bring the entire length of the foxing area into contact with the brush, the flexible strip extending substantially flatwise transversely of the upper of the shoe with one edge of the strip coinciding approximately with the line along which the foxing is to lie and defining the line of demarcation between coated and uncoated surfaces.

It will be apparent that cement is applied across the edge of the strip both to the outer surface of the strip and to the foxing area. The portion of the brush beyond this line rests upon the strip, as the edge of the latter projecting from the guide is flexed and carried toward it by the pressure of the work, said strip thus tending to hug the upper of the shoe and entirely shielding from the cement the surface of the upper which is to remain uncoated. Therefore, beyond determining that in the advance of the shoe the previously-indicated relation is maintained, no care is necessary to produce a perfectly uniform edge of the coated area. Between the application of one part of a piece of work to the brush and the next, the feed of the strip by the roll 52 shifts the shield-strip, so that the surface which has been in contact with the brush is carried away from the point of application of the work for disposal, and a fresh unsmeared section brought into action. The used portion of the strip may be cleansed in some appropriate way, and returned to the reel to be used again, or may be thrown away, it being so slowly advanced that relatively little is used for shielding a number of the shoe uppers operated upon.

Having described my invention, what I claim as new and desire to secure by Letters Patent of the United States is:

1. The method of applying cement to the foxing area of a shoe which consists in inter-

posing an imperforate flexible shielding member between a cement applying device and a predetermined portion of the upper of a shoe to define the exposed foxing area around the lower part of the shoe to which cement is to be applied, flexing the edge of said shielding member to cause it to hug the shoe, applying cement to said exposed area adjacent to the shielded area, and causing relative movement between the applying device and the shoe to transfer the point of application of the cement around the foxing area.

2. The method of applying cement to the foxing area of a shoe which consists in interposing an imperforate shielding strip between a cement applying device and a predetermined portion of the upper of a shoe to define the exposed foxing area around the lower part of the shoe to which cement is to be applied, applying cement to said exposed area adjacent to the shielded area, causing relative movement between the applying device and the shoe to transfer the point of application of the cement around the foxing area, and moving the shielding strip to present a fresh surface to the shoe so that the used portion of the shielding strip may be cleansed or renewed.

3. That method of applying cement to the foxing area of a shoe which consists in bringing an applying device, an imperforate shielding device and a shoe support into cooperative spaced relation whereby the shielding device will protect the portion of the upper of a shoe lying above the foxing area from the application of cement, positioning a shoe in operative relation to said support, shielding device and cement applying device with the shielding device lying at a small angle against the shoe, and causing relative movement of the shoe and the applying device without disturbing the spaced relation of the shoe support and the shielding device to apply cement both to the outer side of said shielding device and to the unshielded foxing area whereby a sharply defined line of demarcation between the coated and uncoated areas will be produced.

4. That method of applying cement to the foxing area of the upper of a shoe the adjacent portion of which upper is shielded by an imperforate flexible member lying flatwise against the upper to prevent the application of cement to said shielded portion, which is characterized by causing a relative movement of translation between an applying device and the shielded shoe to coat the whole vertical extent of each successive portion of the foxing area at any part of the shoe which is brought into cooperative relation with the applying device by applying a stripe of cement which is wider than said foxing area so that it overlaps the flexible shielding member and is thereby accurately

defined on the shoe at the edge of the foxing area.

In testimony whereof I have signed my name to this specification.
